poration of New York

Application November 22, 1944, Serial No. 564,614

10 Claims. (Cl. 242—75)

1
This invention relates to web supply mechanisms for machines such as printing machines that operate on a web fed from a web roll, and has particular application to mechanism for use with high speed rotary printing machines used for printing newspapers and similar products.

In operating a high speed web printing machine, it is desirable to replace an expiring web roll with a new roll while the machine is operating at full printing speed, and meanwhile to maintain tension on the web being fed, at a substantially constant value. The invention herein shown is applied to a structure similar to that disclosed in Lundquist et al. Patent No. 2,155,430, granted April 25, 1939, and in combination therewith provides automatic web tension controlling mechanism that operates to maintain substantially constant tension on a web being fed from a web roll in normal feeding position, and also when the roll approaches exhaustion and is moved into an expiring position to be replaced by a new roll. It is an object of the invention to provide an improved means for controlling the tension of a web fed to a printing machine from new web rolls carried on a support that is rotated to bring rolls successively into the web feeding position, and in which the support is provided with a separate brake for each web roll, and these separate brakes are successively brought into action to automatically control the web tension during the period immediately preceding the replacement of one web roll by another web roll.

Another object of the invention is to provide a new and improved method of successively operating and automatically controlling a plurality of brakes carried by a rotatable web roll support.

With the foregoing and other objects in view, which will appear in the following description, the invention resides in the combination and arrangement of parts, and in the details of construction hereinafter described and claimed.

The preferred embodiment of the invention is illustrated in the accompanying drawings, wherein:

Figure 1 is an elevational view of a web feeding mechanism to which the invention is applied, as seen from one side of the device;

Figure 2 is a view taken along the line 2—2 of Figure 1 and looking in the direction of the arrows;

Figures 3 and 4 are enlarged views of portions of the mechanisms shown in Figure 1;

Figure 4a is a perspective view of a portion of the mechanism shown in Figure 4;

2
Figure 5 is a view showing the association of various control switches and other devices, with the mechanism shown in Figure 1;

Figure 6 is a schematic electrical diagram showing the switches and the connections employed in controlling the web roll supply mechanism;

Figure 7 is a diagrammatic view showing some of the major components of the web supply mechanism in the normal web feeding position;

Figure 8 is a view showing the mechanism in a position intermediate of that shown in Figures 7 and 9;

Figure 9 is a view showing one of the web rolls in the web splicing position and one of the rolls in the expiring position;

Figure 10 is a view showing the mechanism immediately after the web from the expiring roll has been spliced to the web of the replacement roll;

Figure 11 shows a modified form of portions of the mechanism shown in Figures 1 to 10;

Figure 12 is a sectional view taken along the line 12—12 of Figure 11 looking in the direction of the arrows.

Referring to the drawings, the invention is shown in Figures 1 to 10 as applied to a web roll reel capable of moving replacement web rolls from a loading position, to a web splicing position, to a feeding position, and then to an expiring position. The reference character 11 indicates a frame member of a printing machine, to which webs are fed from web rolls.

Additional members (not shown) support the usual printing cylinders, web guide rollers 12 and other devices. A web roll support or reel 13 includes a pair of spiders 13a for carrying a plurality of web rolls, the spiders being secured to a shaft 14 which is rotatably supported by a pair of pedestals, one of which is shown at 15. A motor 16 (Figure 5) is arranged to rotate the reel in either direction and arms 17 support the web rolls on rotatable cones in a conventional manner. In Figures 1, 5, and 8 to 10, a first web roll 18 is shown in an idle position, and a second web roll 19, which will hereinafter be referred to as the replacement web roll, is shown mounted on the reel and in or approaching the splicing position. In Figures 1, 5, 7, 8 and 9, a third web roll 21, which will hereinafter be referred to as the expiring web roll, is shown in various positions from the feeding position (Figure 7) to the expiring position (Figure 9), and has a web 22 running therefrom.

Means is provided for regulating the tension of

the running web by either a main braking mechanism which applies braking pressure to the surface of the web roll, or by an auxiliary braking mechanism which applies a brake at the core of the roll.

The main braking mechanism, which is similar to that shown in Patent 2,155,430, includes endless running belts 23, pulleys 24 and 25, and a third pulley 26 having a movable axis 27. A suitable drive indicated at 28 is provided for the drive pulley 24 and operates the belts at a speed slightly slower than the speed of the running web, thus providing a constant braking action on the surface of the web roll. A shaft 29 rotatably supporting the pulley 25 has arms 31 fixed thereto that are arranged to mount the movable pulley 26 at their extreme ends. While the endless belt mounting is set forth in the singular, it is to be understood that more than one belt is generally used.

A motor 32 connected to the power circuit L4, L5, and L6 by reversing contactors MB and LB (Figure 6) is provided with a reduction gear 34, and a bevel pinion 35 for lowering or raising the belt arms 31. The pinion 35 meshes with a bevel gear segment 36 fixed on the shaft 29, and when the motor is energized, the gear segment will be partially rotated in a clockwise or counter-clockwise direction and thereby rotate the shaft 29 and swing the arms 31. Thus, the braking pressure of the belts is varied by raising and lowering the arm 31. A cam 30 (Figure 5) on the segment 36 opens a normally-closed belt-arm "up limit" switch 40 when the belt arms 31 are raised to their upper limit.

A web tension controlling means in the form of a floating roller 37 (Figure 5) is supported in a loop in the running web 22 and changes its position when the web tension is increased or decreased. The floating roller is rotatably held in pivotally supported arms 38, secured to an arm 39 carrying a cam 41 arranged to operate a "more tension" switch 43 and a "less tension" switch 44 in a manner well known in the art. When the tension on the running web increases, the floating roller 37 will rise and close the "less tension" switch 44, and when the tension is decreased, the floating roller will descend and close the "more tension" switch 43. Although not shown, it will be understood that either the cam 41 or the switches 43 and 44 will be adjustable to regulate the amount of tension applied by the belt 23. Solenoids 45 and 46 (Figure 6), operate the belt-arm raising and lowering contactors LB and MB, the function of which will be described herein-after.

A limit switch 49 is carried by the arm 31 and is operated by a lever 51 hinged to the arm 31, the lever 51 contacting the inner surface of the belt 23 when the arm 31 reaches its lowermost position. It will be understood that a limit switch 49 is used with each belt employed.

An auxiliary or spindle braking mechanism, that is capable of supplying braking at the core of the web roll, comprises mechanism herein shown mounted on the arms 17 of one of the spiders 13a. Each of these spiders (Figures 1 and 2) has a hub extension 52 concentric with the main shaft 14 on which is rotatably mounted a combined cam 53 and sprocket wheel 54. On the same hub and outside of the sprocket wheel 54, a ring 55 is loosely held by a plurality of washers 56 and bolts 57 screw threaded into the hub 52. The ring 55 is held against rotation by links 58 pivotally fastened to the pedestal 15 and to the

ring. The ring 55 supports a timer switch 59 (Figure 5) and a limit switch 60 (Figure 1), the latter being operated by an auxiliary cam 61 carried by the sprocket wheel 54. As hereinafter described, the limit switch 60 and the cam 61 cooperate to stop the cam 53 in a "reset" position. A bracket 62 (Figure 1) is secured to a lower portion of the ring 55 by bolts 63. A motor 64 with a speed reduction gear (Figures 1 and 2) is connected to the power circuit L4, L5, and L6 by reversing contactors MC and LC (Figure 6), and is mounted on a lower portion of the bracket 62 by the bolts 65 (Figure 1). The output shaft 66 of the speed reducer carries a drive sprocket 67 for driving a chain 68 that in turn drives the herein-before mentioned sprocket 54 and cam 53. The cam 53 is formed with a lower portion as indicated at 69 and progressively increases in height in a counter-clockwise direction as seen in Figure 1 to a high portion indicated at 71.

Solenoids 72 and 73 (Figure 6), actuate the motor contactors LC and MC and thus control the motor 64 (Figure 1) and operate the cam 53, when energized by either of a pair of switches 74 or 75 (Figures 5 and 6) that are operated by a cam 76a secured to an arm 76b that is operated by a spring biased floating roller 76. If the tension of the running web increases beyond a pre-determined amount, the roller 76 will operate the cam 76a to close the switch 75 and energize the solenoid 72; or if the web tension decreases the roller 76 will operate the cam 76a to close the switch 74 and energize the solenoid 73, thus decreasing or increasing the tension of the web as required.

Although not shown, it will be understood that either the cam 76a or the switches 74 and 75 will be adjustable to regulate the amount of tension applied by a brake 77.

Each of the arms 17 of one of the spiders 13a carries a spindle brake mechanism 77 arranged to apply a brake to the core of a web roll when it is in the feeding position, the expiring position, or in any position therebetween.

Each brake mechanism 77, as herein shown, comprises a brake band 77b (Figure 4) cooperating with a brake wheel 80. One end of the brake band is pivotally secured to an arm 78 of a rocking lever 79, and the other end of the brake band 77b is adjustably secured to an end of two spaced links 81 by means of the pin 81a, threaded bolt 82, and nuts 83. The lever 79 is pivotally secured to the reel arm 17 by means of a stud 84. A short arm 85 of the lever 79 (Figure 4a) is connected by a pin 85a to a bifurcated portion of a handle 100. The other ends of the links 81 are secured by a pin 81b to an intermediate portion of the bifurcated handle 100. The lever 79 is rocked about the stud 84 by an operating rod 86 connected to an arm 87 at 88. By manually moving the handle 100 toward the left in Figure 4, the brake 77 can be completely released. This is usually done when placing a new web roll in the support, and the brake 77 remains released until the roll in feeding position approaches exhaustion. A spring pressed rod 89, supported from a bracket 91 secured to the arm 17 is connected to the arm 87 at 92, and biases the lever 79 in a clockwise direction. The lower end of the operating rod 86 has a hollow portion 93 (Figure 3), and a collar 94 that is arranged to extend into and abut against a spring 95. Extending inside the hollow portion of the rod 86 and also inside the spring 95, is a second rod 96, having a collar 97 for engaging the spring 95.

The outer end of the second rod 96 is adjustably secured to one end of an arm 98 having a slotted hole 99 (Figure 1), and the other end of the arm 98 is pivotally secured to the reel arm 17 by a stud 101. A second arm 102, is also pivotally mounted on the stud 101, and is formed integral with the arm 98. The arm 102 carries a cam roller 103 for engaging the cam 53. The cam 53, roller 103, rods 88 and 96, and the brake band 77b, together with the other parts of the braking mechanism, are thus so located that braking force may be applied to a web roll located either in the feeding position, or the expiring position, or anywhere between these positions, and by turning the cam 53 to present either a higher portion or a lower portion to the roller 103, the braking force may be regulated. When the cam 53 is rotated clockwise so as to present a higher portion of the cam to the roller 103, the braking force is increased. As the roll and the brake move from the running position to the expiring position, the cam 53, under control of the roller 76 and the motor 64, is automatically rotated counter-clockwise to apply the proper pressure to the brake and thus maintain a constant tension on the web 22. As the tension in the web varies, the cam is moved clockwise or counter-clockwise to regulate the pressure as required.

Twin splicing arms similar to those shown in Horton Patent No. 2,182,760, are indicated generally by the reference character 104, and comprise a pair of brush supporting arms 105 carried on a shaft, and a pair of knife supporting arms 106 carried by a sleeve, all of which are movable about the same axis 107. A beam is secured between the pair of brush arms, and brushes 108 are mounted on the beam. The pair of cutter arms support a web deflector and cutter sheath 109, secured between their outer ends. The two structures are normally joined together, in a manner similar to that shown in Patent 2,182,760, by a latch having a hook 112 (Figure 5) secured to the knife supporting arm, and a pin 113 secured to the brush supporting arm. The latch mechanism has a solenoid 115 for releasing the latch when the solenoid coil is energized.

Since the two parts of the twin structure are normally latched together, they will move in unison when lowered from the non-operating position shown in Figure 5 to the operating position shown in Figure 1. Counter balance and operating spring members, which are fully described and illustrated in the patents hereinbefore mentioned, control the movement of the arms.

An operating handle 116 pivotally supported at 117 has an arm 118, the outer end of which is connected by a chain 119 to the brush supporting arm 105. When the splicing arms 104 are lowered, the operating handle 116 is automatically lowered into an operating position. When the handle 116 is lowered, a cam member 121 will open a switch 122. A second cam member 123, also associated with the operating handle 116, closes a switch 124 when the handle 116 is operated to its fully "down" position in a manner hereinafter described. An auxiliary cam arm 125 associated with the splicing arms 104 is arranged to open two switches 126 and 127 when the splicing arms are moved to the lowered position, and to allow these switches to close when the arms are raised.

The motor 16 (Figure 5) which rotates the reel 13 by means of a worm 128, and a worm wheel 129, is electrically connected to the pair

of reversing contactors F and R (Figure 6) that have operating solenoids 131 and 132. The contactor F will operate the motor 16 to turn the reel 13 in a forward or counter-clockwise direction, while the contactor R will operate to turn it in a reverse direction.

Each arm 17 of one reel spider 13a is equipped with an operating rod 135 similar to that shown in Patent 2,141,137, for engaging a cam surface 136 carried by one of the spindles that support each web roll. The other end of the operating rod 135 is provided with a shoe 137 for closing the contacts of the switch 59 at a certain point in each revolution of the web roll 19. In addition to the electrical contactors and switches previously described, the web supply mechanism includes solenoid operated relays 139 and 141, which are operated from the main controller for the printing machine. The relay 139 is actuated when the machine is being driven at a slow, or web threading speed, and the relay 141 is actuated when the machine is being driven at any regular running speed. The solenoid 139 (Figure 6) operates a pair of switches 143 and 144, and the solenoid 141 operates switches 145, 146 and 147. An impulse switch 149 is driven by a motor 148 (shown diagrammatically in Figure 6), that through a cam 150 opens and closes the switch 149 at a predetermined rate. By this mechanism the motors 32 and 64 are energized intermittently, so the braking action of the belt 23 and the band 77 is increased or diminished gradually.

An automatic reel rotation relay comprises a solenoid 151 and a switch 152. A first control relay comprises a solenoid 153 and four switches 154, 155, 156 and 157. A belt raising relay comprises a solenoid 159, and switches 161, 162, 163 and 164. A second control relay comprises a solenoid 165 and switches 166 and 167. A splicing relay comprises a solenoid 168, and switches 169, 171 and 172. A transfer relay comprises a solenoid 173 and switches 174 and 175. An auxiliary "reset" relay comprises a solenoid 176 and switches 177 and 178. A number of push-button stations are shown and include a "start-stop" push-button comprising a "start" switch 181 and a "stop" switch 182, a "forward" push-button comprises switches 183, and 184, a reverse push-button comprises a switch 185; a "reset" push-button comprises switches 186 and 187; a "belt-up" push-button station comprises switches 188 and 189; and a "belt-down" push-button comprises switches 191 and 192.

A manually operated switch 193 is provided, which when opened, prevents automatic operation of the tension control mechanism, but permits manual control.

If it is assumed that the printing machine, to which the web 22 is being fed, is operating at full speed, the solenoid 141 will be energized and its switches 145, 146 and 147 will be closed, or if operating at web threading speed, the solenoid 139 will be energized and its switches 143 and 144 will be closed. The reel 13 will support the roll 21 in the feeding position as shown in Figure 7 with the belt 23 pressing against the surface of the roll. Since the arms 31 are lowered, the solenoid 153 will be energized through the switch 40. At this time the tension on the web 22 will be governed by the belt 23 under the control of the switches 43 and 44, operated by the floating roller 37. During this period of normal web feeding, all of the auxiliary brakes 77 operated by the cam 53 will be released by the

handles 100 being moved toward the left as shown in dotted lines in Figure 4 and the cam 53 will have been "reset" to a position anticipating the application of a small amount of braking to the core of the roll in the feeding position.

When the running roll 21 (Figure 7) nears exhaustion, and it becomes desirable to transfer the web feed from the feeding web roll 21 to the replacement web roll 19, the handle 100 on the arm 17 carrying the roll 21 will be moved counter-clockwise to the right as shown in Figure 4, to effect application of the brake 11. This brake is so adjusted that when it is thus applied, it will tend to cause a relatively light retarding action on the rotation of the roll, and increase the tension on the running web, but as the brake is applied, the belt 23 will be automatically raised and the tension on the running web will remain substantially constant. When the web feed is to be changed to the replacement roll 19, the start button switch 181 (Figure 6) will be manually closed. This raises the belt 23 by energizing the solenoid 159 (Figure 6) by a circuit extending from a line L-1 through switch 122, conductor 211, solenoid 159, switch 154, and the "start" push-button switch 181, to line L-2. Energizing the solenoid 159 closes the switch 181 to energize the solenoid 45 by way of a circuit which extends from the line L-1, through the switch 181, switch 155, and through the solenoid 45, to the line L-2. This closes the motor contactor LB and operates the motor 32 to raise the belt 23 to the position shown in Figure 8.

Closing the "start" button 181 (Figure 6), also energizes the solenoid 151 of the reel rotation relay by a circuit that extends from the line L-1, through the switch 122, a branch of the conductor 211, switch 210, solenoid 151, conductor 212, and through the "start" button 181, to the line L-2. This relay is maintained by a circuit which includes the switch 152, a conductor 213 and the "stop" push-button switch 182. The switch 152 controls a maintaining circuit for the solenoid 151.

Energizing the solenoid 159 by the push-button switch 181 also causes the cam operated brake on the arm supporting the running roll 21 (Figure 7) to become operative, as it closes the switch 162 (Figure 6) and energizes the solenoid 165 through a circuit from the line L-1, through the manually-operated switch 193, a branch of the conductor 214, switch 146 (then closed), conductor 215, switch 162, and through the solenoid 165 to the line L-2. This solenoid 165 is maintained by a circuit extending from line L-1 through the manual switch 193, a branch of the conductor 214, switch 146 (then closed), conductor 215, "reset" push-button switch 186, switch 175, switch 166, and through the solenoid 165 to line L-2. Energizing the solenoid 165 closes the switch 167, thereby connecting L-1 to the switches 74 and 75, which indirectly control the brakes 11. The circuit which accomplishes this may be traced from the line L-1, through the manual switch 193, a branch of the conductor 214, impulse switch 149, a conductor 216, and through switch 161 (then closed) to either the "less tension" switch 75, or the "more tension" switch 74, whichever happens to be closed. If the "less tension" switch 75 is closed, the solenoid 72 will be energized to operate the motor 34 by closing the contactor LC to rotate the cam 53 (Figure 1) to present a lower portion to the roller 103 and thereby apply less braking by the brake 77 controlling the web roll 21, whereas if

the more tension switch 74 is closed, the solenoid 73 will be energized to operate the motor 34 by closing the contactor MC to rotate the cam 53 to present a higher portion to the roller 103 and thereby apply more braking on the web roll.

As the belt 23 is raised by operation of the "start" button, the brake 77 on roll 21 automatically becomes more effective and by the time the belt leaves the surface of the roll 21, control of the tension in the web running to the machine has been transferred from the belt 23 to the belt 77.

When the belt arm 31 reaches its fully raised position, the switch 40 (Figures 5 and 6) will be opened, deenergizing the solenoid 153 and opening the switch 155, thus deenergizing the solenoid 45 to stop the belt arms from further upward movement. The switch 154 will also be open, the coil 159 deenergized, and the switch 184 closed, and with the "start" button 181 held closed, the solenoid 151 of the forward contactor FFF of the motor 16 will be closed, thus rotating the reel 19 counter-clockwise and moving the roll 19 toward the running web 22.

The circuit that energizes the solenoid 151 extends from line L-1, through a switch 122, a branch of the conductor 211, the solenoid 151, a conductor 217, switch 164, switch 183, conductor 212, switch 152, conductor 213 and through the push-button 182, to the line L-2. When the roll 19 reaches the web splicing position (Figure 9), one of the cams 220 (Figure 5) on the spider 19a will operate the switch 210, deenergizing the solenoid 151 (Figure 6), opening the switch 152, deenergizing the solenoid 151, and thus stopping the rotation of the reel 19.

When the web from the roll 21 is nearly exhausted, the arms 104 are lowered manually to the position shown in Figures 1 and 9, and the operating handle 116 is simultaneously lowered to the position shown by the dash lines in Figure 5. The interlock switch 122 is thereby operated to interrupt the circuit to the solenoid 151 and 152 (Figure 6), and thereby prevent inadvertent operation of the reel rotation motor 16. Simultaneously, the two interlock switches 126 and 127 are opened. The switch 126 opens the circuit to the solenoid 173 of the transfer relay, and the second switch 127 opens the circuit to the belt lowering solenoid 46, thus preventing automatic operation of the belt arm in a direction which would apply braking to the periphery of the web roll 19.

In order to cause the replacement roll to rotate at a peripheral speed nearly equal to the speed of the running web, the belt arm 31 is lowered by manually closing the "down" push-button switch 192, which energizes the solenoid 46, by a circuit from the line L-1, through the push-button switch 192, switch 40, and through the solenoid 46 to the line L-2. The solenoid 46 closes the contactor MB, and the motor 32 operates to lower the belt arm 31.

After the replacement web roll has been rotating at web speed, for a few seconds, the handle 116 is pulled down to dotted line position in Figure 5, and the splicing switch 124 thus closed. While the handle 116 is held in this position, a circuit through the solenoid 168 (Figure 6) is closed when the cam 136 closes the timer switch 59. The circuit may be traced from line L-1, through the solenoid 168, splicing switch 124, and through the splicing timer 59 to the line L-2. The first closure of the splicing timer 59 energizes the solenoid 168 which closes the switch

171, energizing the splicing solenoid 115 through a circuit extending from the line L-1, through switch 171, and through the splicing solenoid 115 to the line L-2. This releases the brush 108 and the web from the roll 21 is pressed against the roll 19 (Figure 9). Simultaneously, the switch 172 energizes the solenoid 176 of the auxiliary reset relay, by a circuit which may be traced from line L-1 (Figure 6), through the switch 172, and through the solenoid 176 to the line L-2. The auxiliary reset relay is maintained by the closing of switch 177 which establishes a maintaining circuit from the line L-1, through the cam reset switch 60, circuit 171, and through the solenoid 176 to the line L-2. The second closing of the splicing timer 59 again energizes the splicing solenoid 115 which this time operates a knife blade held in the sheath 109, to sever the web 22 running from the expiring roll 21 (Figure 10). Mechanism that may be employed for thus releasing the brush 108 and then releasing the solenoid 115, is fully disclosed in Patent 2,182,760.

As soon as the web splice has been made, the splicing arms 104 are manually raised to the position shown in Figure 10, and the interlock switches 122, 126 and 127 return to the positions shown in Figure 5. This return movement of the switch 126 "resets" the cam 53 (Figure 1) so its low portion 69 is presented to the roller 103 on the arm carrying the roll 19, by energizing the solenoid of the relay 173 (Figure 6) through a circuit from the line L-1, through the switch 169, switch 126, switch 178 (then closed), a conductor 218, and through the solenoid 173 to the line L-2. This energizes the solenoid 73 of the cam operating contactor by a circuit which extends from line L-1 through switches 169, 126, 178, and 174, a conductor 219, and through the solenoid 73 to line L-2. Energizing the solenoid 73 closes the contactor MC and causes the motor 64 to rotate the cam in a clockwise direction. Energizing the solenoid 173 also opens the switch 175 and prevents automatic operation of the brakes 77 by opening the maintaining circuit of the solenoid 165.

When the cam 53 reaches the reset position, it is stopped by switch 60 which is opened by engaging the cam 61 (Figure 1), deenergizing the solenoid 176 opening the switch 178, and deenergizing the solenoid 173, opening the switch 174, deenergizing the solenoid 73 and stopping the motor 64.

The return movement of the switch 127 causes the control of the belt arm 31 to pass to the floating roller 37 which lowers the arm 31 and then automatically regulates the tension of the web running from the roll 19, by a circuit which may be traced from the line L-1 (Figure 6), through the manual switch 193, a branch of the conductor 214, impulse switch 149, conductor 216, switch 145, conductor 221, switches 147, 127, 43, and 151 push-button switch 191, switch 49, and through the solenoid 46 to the line L-2. It will be noted that the belt controlled tension has thus again become operative and regulates the tension of the web running from the roll 19 that now becomes the feeding roll and that the brakes 77 are inoperable. Pressing the push-button switch 185 will rotate the reel 13 in the clockwise or reverse direction and thus place the roll in the normal running position, as shown in Figure 7.

The reel 13 may be rotated in a clockwise direction by manually closing the reverse push-button switch 185, or in a counter-clockwise direc-

tion by closing the forward push-button switch 184.

The modified form of the mechanism shown in Figures 11 and 12 is similar to that shown in Figures 1 to 10 except that a manual means for operating the auxiliary brake 77 is included. An arm 19a is equipped with an extension 231, having a clearance hole through which a threaded stud 232 extends, one end of the stud being secured in a boss 233 on the arm 17. A knurled adjusting nut 234 is a screw threaded on the stud 232, which is provided with a shoulder 236 that prevents the nut from being completely unscrewed therefrom.

An arm 98a and an arm 102a are separable instead of being solidly joined as are the arms 98 and 102 of the previously illustrated embodiment.

A bracket 237, carried by the arm 17, rotatably supports a bolt 101a (Figure 12), having a collar 244 formed as an intermediate portion of the bolt, and a nut 246 screw threaded and pinned to the left end thereof. When a winged nut 239, screw threaded to the right end of the bolt 101a is tightened, it secures the arms 98a and 102a to the bolt with the arm 98a abutting the right face of the collar 244. Positioned between the disc-like ends of the arm 98a and 102a and surrounding the bolt 101 is a compression spring 241. The disc-like end of the arm 102a is provided with a pair of teeth 242, which when the nut 239 is tightened engage notches 243 formed in the disc-like ends of the arm 98a to hold the two arms in proper relationship.

Under normal operating conditions the wing nut 239 will be tightened, to clamp the arm 102a to the arm 98a and the nut 239 will be unscrewed so as not to engage the arm 231. If, in the case of a failure of either automatic tension controlling mechanism, it is desired to operate the brake 77 by hand, the wing nut 239 is loosened sufficiently to allow the spring 241 to disengage the teeth 242 from the notches 243, and the knurled nut 234 is tightened by hand until it engages the extension 231. The brake 77 can thus be applied or released by tightening or loosening the nut 234.

It will be understood that the invention may be embodied in other specific forms without departing from the spirit or essential attributes thereof, and it is therefore desired that the present embodiment be considered in all respects as illustrative and not restrictive, reference being made to the claims rather than to the foregoing description for an indication of the scope of the invention.

What I claim is:

1. A web supply mechanism comprising a first web tension controlling roller, a pair of switches operated by the said first roller, a reversible motor controlled by the pair of switches, a movable pulley carrying a running belt for applying braking to the periphery of the web roll and adjustable by the motor, a second web tension controlling roller, a second pair of switches operated by the said second roller, a second reversible motor controlled by the second switches, and a spindle brake for applying braking to the core of the web roll and controlled by the second reversible motor.

2. In a web supply mechanism for a machine operating on a web drawn from a web roll, a rotatable roll support adapted to move a web roll from a loading position to a splicing position, to a feeding position and to an expiring position, a braking mechanism associated with the roll

support for applying braking to the core of the web roll from feeding to expiring position and including cam mechanism comprising a cam element carried by and rotatable with the roll support and a cooperating cam element rotatable about the rotary axis of the roll support and independently thereof, the cam elements being formed for regulating the braking force according to the relative angular positions of the two said cam elements within a restricted angular range which is of less extent than the angle between feeding and expiring positions, a motor for rotating the second said cam element, an angularly fixed support for the said motor, and control means responsive to variation in tension of the running web and to movement of the said roll support for operating the motor, to cause the said rotatable cam member to follow the roll support in its rotation and to adjust its angular position with reference thereto for regulating the braking force applied to the web roll in accordance with the tension of the web.

3. Web supply mechanism according to claim 2, on which the rotatable roll support comprises a roll supporting member which is slidably adjustable for accommodating web rolls of different widths and which carries the first said cam element, and the motor support is also slidable to maintain its position relative to the slidable roll supporting member.

4. Web supply mechanism according to claim 2, comprising also a limit switch, and operating means therefor attached to the rotatable cam element, for resetting the rotatable cam element in a predetermined position, relative to a roll in feeding position, following each splicing operation.

5. In a web supply mechanism for a machine operating upon a web running from a web roll and including a web roll support adapted to move a replacement roll from a loading position to a splicing position, to a feeding position and to an expiring position; a first braking mechanism governed by a first floating roller held in a loop of the running web and adapted to apply braking force to the surface of a web roll in the feeding position, a second braking mechanism governed by a second floating roller held in a loop of the running web and adapted to apply braking force to the web roll in any position from the feeding position to and including the expiring position, and means to make the first floating roller ineffective and the second floating roller effective when a web splice is about to be made.

6. In a web supply mechanism for a machine operating upon a web running from a web roll and including a web roll support adapted to move a replacement roll from a loading position to a splicing position, to a feeding position and to an expiring position; a normally active braking mechanism adapted to apply braking force to the surface of a web roll in the feeding position, and a normally inactive braking mechanism adapted to apply braking force to the web roll in any position from the feeding position to and including an expiring position; means for moving said roll support, and common control means for simultaneously energizing the last said means and activating the normally inactive braking mechanism.

7. In a web supply mechanism for a machine operating upon a web running from a web roll and including a web roll support adapted to move a replacement roll from a loading position to a splicing position, to a feeding position and to an

12
expiring position; a first braking mechanism governed by a first floating roller held in a loop of the running web and adapted to apply braking force to the surface of a web roll in the feeding position, a second braking mechanism governed by a second floating roller held in a loop of the running web and adapted to apply braking force to the web roll in any position from the feeding position to and including the expiring position, means to make the first floating roller ineffective and the second floating roller effective when a web splice is about to be made, and means to again make the first floating roller effective after the splice has been made.

8. In a web supply mechanism for a machine operating upon a web running from a web roll and including a web roll support adapted to move a replacement roll from a loading position to a splicing position, to a feeding position and to an expiring position, a normally active braking mechanism adapted to apply braking force to the surface of a web roll in the feeding position, and a normally inactive braking mechanism adapted to apply braking force to the web roll in any position from the feeding position to and including an expiring position; means operable while a roll is in feeding position for rendering said normally active braking mechanism inactive, and common control means for simultaneously energizing the last said means and activating the normally inactive braking mechanism.

9. Web supply mechanism according to claim 8, comprising also splicing mechanism and means operable by movement thereof for making the first mentioned braking mechanism again active and the second mentioned braking mechanism again inactive after a splice has been made.

10. In a web supply for a machine operating upon a web running from a web roll and including a rotatable web roll support adapted to carry a plurality of rolls and move the same successively from a loading position, to a splicing position, to a feeding position and to an expiring position, a normally active braking mechanism adapted to apply braking force to the surface of a web roll in the feeding position, normally inactive spindle brakes carried by the rotatable web roll support, one such spindle brake being provided for each of the plurality of rolls, a normally inactive common actuating mechanism for said spindle brakes operable to apply braking force to a selected brake and rotatable about the roll support axis for maintaining a fixed angular relation to the selected brake while a roll controlled thereby is in feeding position, during its movement to expiring position and in its expiring position, a floating roller tension control responsive to variation in tension of the running web for controlling the spindle brake actuating mechanism, means for gradually rendering the normally active roll surface braking mechanism inactive, and means operable simultaneously therewith for activating the spindle brake actuating mechanism, whereby a spindle brake may automatically take over control of a roll, as the normally active surface braking mechanism becomes inactive, and maintain such control as the roll is moved from feeding position to expiring position.

WILLIAM C. WIEKING.
